UNITED STATES PATENT OFFICE.

WILLIAM H. KEEFER, OF UNION BRIDGE, MARYLAND.

TELEPHONE STAND.

Application filed December 4, 1923. Serial No. 678,457.

To all whom it may concern:

Be it known that I, WILLIAM H. KEEFER, citizen of the United States, residing at Union Bridge, in the county of Carroll and 5 State of Maryland, have invented certain new and useful Improvements in Telephone Stands, of which the following is a specification.

This invention relates to certain new and 10 useful improvements in telephone stands, and has particular reference to an improved adjustable receiver supporting means for telephone stands.

The primary object of the invention is to 15 provide a receiver support for telephone stands which may be conveniently and expeditiously adjusted into proper position for use.

Another object of the invention is to provide 20 a receiver support of the above kind which embraces the desired qualities of simplicity and durability of construction, as well as efficiency in operation.

A further object of the invention is to provide 25 a greatly simplified and improved form of telephone receiver support that is capable of use in connection with existing telephone stands with the necessity of merely substituting of a special screw carrying fitting for 30 the screw which pivotally connects the transmitter to the telephone stands now in use, the screw of the fitting being employed in lieu of the usual screw.

Other objects will become apparent as the 35 nature of the invention is better understood, and the same consists in the novel form, combination and arrangement of parts herein-after more fully described, shown in the accompanying drawing and claimed.

40 In the drawing, wherein like reference characters indicate corresponding parts throughout the several views:

Figure 1 is a front elevational view of a 45 telephone stand equipped with a receiver support constructed in accordance with the present invention.

Figure 2 is a top plan view of the device shown in Figure 1.

Figure 3 is an enlarged fragmentary detail sectional view, taken substantially upon the line 3-3 of Figure 2, and

Figure 4 is a view similar to Figure 3 taken upon the line 4-4 of Figure 2.

Referring more in detail to the drawing, 55 5 indicates in general a conventional form of telephone stand embodying a base 6, with

a central rigid standard or upright post 7, the upper end of which is forked to provide a pair of legs 8, between which is pivoted the ear 9, that is rigid with the rear side of the 60 usual transmitter 10, by means of which said transmitter may be vertically swung for adjustment.

The present invention embodies a special fitting including a sleeve member 11 that is 65 closed at one end and rigid with which closed end is an axial outwardly extending screw bolt 12 that is passed through the aligned openings in the legs 8 and ear 9, in lieu of the usual pivot bolt thereof, for pivotally 70 connecting the transmitter 10 to the upper end of the post 7. The present invention further embodies a receiver supporting arm consisting of a tubular arm or conduit 13, that has one end threaded into the outer end 75 of the sleeve 11 as at 14, and that has its outer end forwardly and inwardly directed as at 15 and 16 respectively, the inner end of the arm 13 inwardly of the screw threaded portion thereof as at 14 being of polygonal 80 form as shown at 17. The sleeve 11 carries a set screw 18, which may be brought into engagement with the polygonal end portion 17 of the arm 13 for securing the latter in 85 the desired position and for preventing the same from turning within the sleeve 11, and it is obvious that the arm 13 may be adjusted by rotation about its longitudinal horizontal axis for positioning said end 16 of the arm 90 13 at the desired elevation, by simply making this adjustment.

Threaded upon the inturned end 16 of the arm 13 is a socket 19 that is provided with inwardly projecting ears 20 upon the end thereof, which ears 20 are disposed between and pivotally connected to ears 21 provided upon the receiver 22, by means of a bolt 23 that may be adjusted for regulating friction between the ears 20 and 21 to maintain the receiver 22 in any adjusted position to which it is swung. When the arm 13 is adjusted properly, as shown, the bolt 23 is substantially vertical, so that the swinging adjustment of the receiver 22 is in a substantially horizontal plane or forwardly and rearwardly. 100 105

The sleeve 11 is provided with an opening, as at 24, while the socket 19 is provided with a similar opening, as at 25, so that the wire may pass into the sleeve 11 through the arm 13 and socket 19 out through the opening 25 to the receiver connection. 110

The adjustment obtained through the provision of the polygonal portion 17 of the arm 13 is merely a means or rough adjustment to suit particular conditions and further adjustment of the arm 13 upon a horizontal longitudinal axis may be made within reasonable limits by merely rotating the sleeve 11 and its attached bolt 12 in the legs 8 of the post 7. The polygonal portion of the arm 17 fitting within a correspondingly shaped portion of the bore of the sleeve 11 also provides efficient means, primarily, for preventing movement of the arm 13 about its longitudinal axis from proper set position relative to the sleeve 11.

From the above, it will be seen that the arm may be rotated about its longitudinal axis by raising or lowering the inturned end 16 thereof to bring the receiver 22 at the desired elevation, and that the receiver 22 may be swung in a horizontal plane forwardly or rearwardly about the bolt 23 for suiting the requirements of the user.

Arranged over the usual opening in the post 7, ordinarily extending through which is the combination control switch and receiver support, not shown, is a suitable hand operated switch 26, for controlling the circuit to the receiver 22.

30 A simple, durable and efficient form of receiver support is thus provided, which may be cheaply and easily manufactured and placed into use.

What I claim as new is:

1. A telephone construction comprising a 35 conduit having its outer end provided with a return bend, a sleeve provided with a bolt by means of which it is adapted to be adjustably connected to the standard of the telephone, the inner end of said conduit 40 being adjustably mounted in the sleeve, a socket into which the outer end of said conduit is adjustable, a receiver, and a pivotal and adjusting connection between the receiver and said socket permitting the receiver to be adjusted in a horizontal plane.

2. In a telephone structure, a conduit having a return bend at its outer end to dispose the outer end in an inwardly extending direction, a sleeve into which the inner end of said conduit is adjustably mounted, said inner end being provided with a reduced polygonal portion, a set screw carried by said sleeve and cooperable with said polygonal portion, a retaining bolt carried by and extending laterally from said sleeve, a nut on the threaded end of said bolt, a socket in which the opposite end of said conduit is adjustably mounted, said socket being provided with ears, a receiver having laterally extending ears cooperating with said first named ears, and a retaining and pivotal bolt passing through said ears to permit said receiver to be adjusted in a horizontal plane.

In testimony whereof I affix my signature.

WILLIAM H. KEEFER.
